United States Patent Office.

JOSEE JOHNSON, OF NEW YORK, N. Y.

Letters Patent No. 105,086, dated July 5, 1870; antedated June 30, 1870.

IMPROVED CLOTHES-RACK.

The Schedule referred to in these Letters Patent and making part of the same.

To all whom it may concern:

Be it known that I, JOSEE JOHNSON, of New York, in the county of New York and in the State of New York, have invented certain new and useful Improvements in Clothes-Racks; and do hereby declare that the following is a full, clear, and exact description thereof, reference being had to the accompanying drawing and to the letters of reference marked thereon, making a part of this specification.

The nature of my invention consists in the construction and arrangement of a "hanging clothes-rack," which, when not in use, can be folded up out of the way.

In order to enable others skilled in the art to which my invention appertains to make and use the same, I will now proceed to describe its construction and operation, referring to the annexed drawing, in which—

Figure 1 is a perspective view of my clothes-rack in position for use, and

Figure 2 is a perspective view of the same when not in use.

My clothes-rack consists of a series of round bars, A A, of any desired length, connected at their ends any suitable distance apart by means of cords *a* and *b*.

The upper or top one of the bars A is provided at one end with a cross-bar, B, forming a T-shaped bar, which has a cord, *d*, attached at each end of the bar B, and forming in the center a loop, *e*.

The cord *b*, which connects the outer ends of the bars A A, passes above the upper bar, and through the knot which forms the loop on the cord *d*, so that said cord *b* can be drawn up when desired, as will be hereinafter described.

The clothes-rack thus constructed is suspended from a pin or nail by means of the loop *e*, in such a manner that the cross-bar B will bear against the wall,

when the bars A A will be held in a horizontal position at right angles with the wall, and clothes can be hung on said bars. If the pin or nail on which the rack is suspended should stand straight out from the wall, it will only be necessary to take a turn in the loop, when it will be as securely fastened as is necessary.

Should the outer ends of the arms or bars A A sag down, it will readily be remedied, by merely drawing up the cord *b*, and shortening it directly under the loop *e*.

When the rack is not in use, the cross-bar B is removed from its position against the wall, and hung on the nail, when the bars A A will hang, as shown in fig. 2, close to the wall, and be out of the way. The lower end of the cord *a* may be provided with a loop, *f*, to be also suspended from the same nail when the rack is not in use, as otherwise the rack might drag on the floor. The cords *a b d* may all be in one piece instead of several, as above mentioned.

This simple, but yet very handy clothes-rack can be made very cheap, and may be easily packed away in a trunk when traveling.

Having thus fully described my invention, What I claim as new, and desire to secure by Letters Patent, is—

The combination of the arms A A, cross-bar B, one or more cords *a b d*, and with or without the loops *e f*, all constructed and arranged as described, to form a hanging clothes-rack, substantially as herein set forth.

In testimony that I claim the foregoing, I have hereunto set my hand this 23d day of December, 1869.

JOSEE JOHNSON.
